UNITED STATES PATENT OFFICE

GEORGE W. GERAU, OF BROOKLYN, NEW YORK.

IMPROVEMENT IN AWNINGS.

Specification forming part of Letters Patent No. 137,772, dated April 15, 1873; application filed September 7, 1872.

To all whom it may concern:

Be it known that I, GEORGE W. GERAU, of Brooklyn, in the county of Kings and State of New York, have invented a new and Improved Ventilating Wing-Awning, of which the following is a specification:

In the accompanying drawing, Figure 1 is a front elevation of my invention. Fig. 2 is a vertical central section, and Fig. 3 a horizontal section, of the same.

Similar letters of reference indicate corresponding parts.

The invention consists of certain improvements in awnings, which will first be fully described and then clearly pointed out in the claim.

A in the drawing is the lower U-frame, by which the awning B is held extended in front of the wall or window-frame C. This frame A is hinged and made up and down adjustable in the ordinary or suitable manner. The front a of the awning is securely connected with the front of the U-frame. Its side wings b b are, however, not so secured, but are provided with hooks or other devices d d, whereby they can be fastened to the face of the wall. When the air is to be admitted at one side of the awning the wing b at that side is unfastened from the wall and swung out, as in Fig. 3, and held out by a rigid brace or bar, D. The inner end of this brace is fitted into a ring or socket, e, that is provided for its reception on the window sill or frame. The outer end hooks into a loop on the wing b. In this manner the wing is held open and air freely admitted to one side of the awning. When the sun

does not strike either side of the awning both wings may be thus opened and a regular draft created in front of the window. At night especially such thorough ventilation will be desirable. To facilitate the opening of these wings their lower parts are detached from the front a, as shown at f in Fig. 1. E E are two inner wings or flaps arranged within the awning near to the wings b b, respectively. They are sewed fast at the junction of the wings b and front a. When one wing b is swung open, as in Fig. 3, the wing E pertaining to it is stretched across the awning diagonally and fastened to the window-frame by hooks or otherwise, making thus a continuation of the open wing b and a clear passage for the entrance of air into the room.

In place of two inner wings, E, but one may be used, fastened to the inner side of a, equidistant from the wings b.

The same principle of invention can be applied to old awnings by merely taking the frame out at the sides.

Having thus described my invention, I claim as new and desire to secure by Letters Patent—

1. The brace D, combined with the side wing b of an awning, substantially as set forth.
2. The awning provided with the inner wing or wings E and with the opening side wings b b, substantially as herein shown and described.

GEORGE W. GERAU.
